(57) **CLAIM**

The ornamental design for a swab, as shown and described.

DESCRIPTION

FIG. 1 is a perspective view of an example of a swab according to the present disclosure;

FIG. 2 is a front view of the example of FIG. 1;

FIG. 3 is an enlarged view of a portion of the example of FIG. 2;

FIG. 4 is a back view of the example of FIG. 1;

FIG. 5 is an enlarged view of a portion of the example of FIG. 4;

FIG. 6 is a top view of the example of FIG. 1;

FIG. 7 is a bottom view of the example of FIG. 1;

FIG. 8 is a right side view of the example of FIG. 1;

FIG. 9 is an enlarged view of a portion of the example of FIG. 8;

FIG. 10 is a left side view of the example of FIG. 1; and, FIG. 11 is an enlarged view of a portion of the example of FIG. 10.

The broken lines shown in FIGS. 1-5 and FIGS. 7-11 illustrate portions of the swab that form no part of the claimed design.
